UNITED STATES PATENT OFFICE.

GUSTAV HERBERT AND OTTO HERBERT, OF SPANDAU, GERMANY.

CIGAR-MAKING MACHINE.

SPECIFICATION forming part of Letters Patent No. 664,949, dated January 1, 1901.

Application filed January 15, 1900. Serial No. 1,317. (No model.)

To all whom it may concern:

Be it known that we, GUSTAV HERBERT, residing at Mittelstrasse 4, and OTTO HERBERT, residing at Radelandstrasse 2, Spandau, German Empire, subjects of the Emperor of Germany, have invented certain new and useful Improvements in Cigar-Making Machines, of which the following is a specification.

Our invention consists of a new and improved cigar-making machine embracing certain novel advantages in its construction, as is hereinafter set forth.

In the accompanying drawings, in which similar letters of reference refer throughout to similar parts, Figure 1 is a sectional view of a cigar-making machine embracing our invention on the line C D, E F, and G H, Fig. 2. Fig. 2 is a sectional view on line A B of Fig. 1, showing the machine closed. Fig. 3 is a sectional view, also on line A B, showing the machine open. Fig. 4 is a view of Fig. 1 seen from the right.

In the construction of our invention we employ two similarly-formed frame-plates *d* and *d'*, each of which is in cross-section approximately a quadrant and in longitudinal form cylindrical. Formed on the corresponding end of each are inwardly-extending tail-sectors *d*², which by a perforated tongue-and-groove formation with pin *f* therethrough are pivotally connected. The opposite adjacent ends of said plates have formed thereon disks *d*³, adapted to lie snugly one against the other, and are each provided with somewhat elliptically-formed slots *k* and *k'*, (see Fig. 4,) through which extend the power-transmitting shafts *o*, and which latter, secured, as hereinafter described, to rollers, are thus allowed free movement with their respective parts when the frame-plates *d* and *d'* are swung about their pivot *f*. Formed on the inner sides of plates *d* and *d'* are corresponding pairs of webs *c* *c'* *c*² *c*³, all lying in planes parallel one to the other, as also to those of the tail-sectors and end disks aforesaid. The webs *c* *c'* form bearings for a plurality of roller series and are of such sector form that when the frame-plates are swung backwardly about the pivot *f* the rear edges of the corresponding webs come in contact, as shown in Fig. 3. Mounted in said webs and extending longitudinally between the

frame-plates are a plurality of roller series, that set of roller series which engage the webs of plate *d* being duplicated in number and arrangement by those in connection with plate *d'*. As these roller series are all similar, it is necessary to describe but one.

From Fig. 1 it will be seen that a conical-shaped roller *i* has its point journaled in a similarly-shaped opening formed in web *c*, where it is held in position by the novel manner in which the opposite end is journaled. This is effected by forming on or securing within the base of roller *i* a neck *e*², which carries a collar *e*³, engaging the opposite side of the bearing-web *c*, which latter is suitably beveled or flanged, as shown in Fig. 1. The extreme outer end of said neck is angularly formed and loosely fits within a similarly-formed opening in the roller *h*, next continuing the series. Roller *h* also carries on its other end a neck *e*, passing through web *c'*, which forms its bearing, and an angular end is here formed on said neck, which enters an opening in a roller *g*. The rollers *g* have necks *e*, provided with an angular opening, each of which receives the inner end of a power-rod *o*. It will be thus seen that if the power-rods be rotated the motion imparted is carried by means of the couplings through the entire series, so that the various rollers *g*, *h*, and *i* are given an equal rotary movement. This movement continues even when the two sets of rollers are swung about their pivoting-pin *f*—that is, when the machine is opened—inasmuch as the power-transmitting shafts *o* are adapted through their end connections with their respective rollers and drivers to retain their power-transmitting connection irrespective as to whether the machine is closed or opened.

The space formed by the two sets when the machine is closed approximates the form of a cigar. It will be noticed, however, that when the machine is closed the outer roller series of each set do not come together, but form a slit *m*, through which the cigar-wrapper can be passed, while to aid the same guide-plates *l* and *l'* are mounted on the frame-plates *d* and *d'*, respectively.

The utility of having the frame-plates adapted to swing open and shut without disturbing the power connection will be seen

from the fact that the rollers, the rotation of which continues when the machine is opened, immediately form the introduced fillings to the shape of the cigar-bunch before the machine is closed again. The advantage of this arrangement is obvious, as with our machine the whole work is done within a shorter time than heretofore.

What we claim as our invention, and desire to secure by Letters Patent, is—

1. A new and improved cigar-making machine having two duplicate frame-plates pivotally connected, a similar set of roller-series mounted in each power-transmitting shaft 15 in connection with each of said roller series and said frame-plates being adapted to swing

open and shut without disturbing said power connection substantially as described.

2. A new and useful cigar-making machine comprising duplicate cylindrical-shaped frame-plates pivoted together and adapted to be opened and closed, sets of roller series mounted in each of said frame-plates and means for imparting a rotary motion to each of said roller series, while said plates are 25 closed or opened, substantially as described.

GUSTAV HERBERT,
OTTO HERBERT.
